COOLING BED

Gustaf L. Fisk, New Fairfield, Conn., assignor to
Mesta Machine Company, West Homestead,
Pa., a corporation of Pennsylvania

Application September 29, 1941, Serial No. 412,802

5 Claims.

(Cl. 80—42)

This invention relates to cooling beds for a variety of products and, in particular, to cooling beds having provisions for the annealing of flat bars in a continuous pack.

Cooling beds having provisions for such pack annealing have been used for many years. Certain forms of such beds are shown in my Patent 1,761,470, Fisk et al. Patent 1,954,123 and Peterson Patent 1,834,728. The known cooling beds, however, have been required to anneal rolled bars of relatively narrow widths only, say up to 4". More recently, it has appeared desirable to subject much wider bars, e. g., up to 8" wide, to pack annealing, but this cannot be accomplished successfully by the structures and mechanisms known previously. In addition, when pack annealing bars on beds of known types, it is found that the bars do not readily separate from each other at the discharge end of the pack. Instead the bars have a tendency to "shingle" so that considerable time and labor are required to separate them preparatory to subsequent handling.

I have invented a novel cooling bed which fully overcomes the aforementioned objections to such beds as previously known. In a preferred embodiment, I provide a plurality of tilttable arms with latch members adapted to engage the upper edge of the rearmost bar of a pack for supporting the bars on edge as they travel across the pack annealing section of a cooling bed. The latch members, pivoted on the tilttable arms, are displaced each time a bar is added to the pack by suitable packing arms. The latch members are then restored by gravity to holding position as the packing arms return to their starting position.

The tilttable arms may be shifted collectively to adjust the latch members to the proper elevation for a particular width of bars to be pack annealed and may also be individually adjusted to bring the ends of all the latch members into alignment.

Means are provided for separating the leading bar from the remaining bars constituting the pack, in such manner as to avoid any "shingling" and to insure a prompt and positive separation.

For a complete understanding of the invention, reference is made to the accompanying drawings, which will be described and explained in detail hereinafter. In the drawings,

Figure 1 is a typical transverse section through a cooling bed with parts in elevation, the showing being largely diagrammatic;

Figure 2 is an end elevation of one of the tiltting arms and its latch member;

Figures 3 and 4 are diagrams illustrating the progressive steps in starting and building a pack of flat bars of small width for progressive cooling in contact with each other, as carried out by the apparatus of Figures 1 and 2; and

Figures 5 and 6 are similar diagrams illustrating the operation of the apparatus in forming a pack of bars of the maximum width.

Referring now in detail to the drawings and, for the present, to Figures 1 and 2, hot rolled bars 10 are received along one side of a cooling bed indicated generally at 11 on a run-in conveyer comprising a plurality of motor-driven rollers 12. Arms 13 are movable longitudinally of the rollers 12 to serve as a "kick-off" by displacing the bars 10 laterally from the rollers.

The cooling bed 11 comprises a sloping skid section 14, an arcuate skid section 15, a packing section 16, a sloping discharge section 17 and a final cooling section 18. The various sections of the bed are composed of skids formed from suitable metal bars supported in any convenient manner, for example, as disclosed in the prior patents above mentioned. The final cooling section 18 may conveniently take the form illustrated at 19 in Patent 1,954,123. The bars forming the packing section 16 with discharge section 17 and the arcuate skid section 15 are pivoted on a longitudinal shaft 19 whereby the packing section may be tilted to discharge bars delivered thereto immediately, in case pack annealing is not desired.

The shaft 19 is also provided with packing arms 20. The edges of these arms have angularly disposed portions 20a and 20b adapted to engage and deliver bars to the packing section 16 at different inclinations, to suit the width of bar handled and subject to pack annealing. These arms serve to move bars successively from a position at the foot of the sloping skid section 14 upwardly over the arcuate skid section 15 to the entering side of a pack of bars disposed on edge, indicated generally at 21. The bars are delivered to the sloping skid section 14, as previously indicated, by the laterally movable arms 13 which act as a "kick-off."

The novel pack supporting means which I have invented particularly for the purpose of maintaining a pack of extra wide bars as well as packs of bars of ordinary widths is indicated generally at 22. It comprises a plurality of arms 23 spaced along the length of the cooling bed and pivoted on pins 24 in the main frame members of the bed supporting the conveyer rollers 12. Each arm 23 has a crank 25 thereon. The arms 23 are rotatable on the pins 24. To effect

this rotation, a shaft 29 having cranks 30 spaced therealong is journaled in the main frame members of the bed. Links 31 are pivoted to the cranks 25 and 30. Each link 31 includes a bar 32 having a sleeve 33 formed at the end thereof and a rod 34 having a clevis at the upper end by which it is pivoted to crank 25 of the arm 23. The lower end of the rod 34 passes through the sleeve 33 on the bar 32 and is threaded to receive nuts 35. A compression spring 36 is disposed on the rod 34 between the clevis end thereof and the sleeve 33. By suitable adjustment of the nuts 35, the spring 36 may be placed under the desired initial compression. When so adjusted, the link 31 serves to transmit positively any force applied thereto less than that necessary to compress the spring further.

Any convenient drive may be provided for the shaft 29, e. g., a suitable motor and gear reducer whereby all the arms 23 along the full length of the cooling bed may be simultaneously operated to position the latch members 37 on the free ends of the arms 23 at the proper level, regardless of the width of the bars to be pack annealed. By means of nuts 35, the bars 23 may also be individually adjusted to bring the projecting ends of the latch members 37 into alignment.

A pack engaging latch member 37 is pivoted to the end of each of the arms 23. The latch members are so positioned relative to their pivot pins that the projecting left hand ends of the members over-balance the right hand ends, whereby the latter normally engage stop pins 38. The latch members 37 serve to support the pack 21 as illustrated in Figure 1, regardless of whether bars of minimum or up to maximum width are being handled.

The operation of the structure shown in Figures 1 and 2, in the handling of relatively narrow bars, will be explained by reference to Figures 3 and 4. When the first bar 10, on being kicked off the conveyer rolls, has slid to the bottom of the sloping skid portion 14, the shaft 19 is operated to rotate the packing arms 20. The portions 20a and 20b thereof engage the bar only at its lower and upper edges, respectively, and move it upwardly around the arcuate skid section. During this movement, the upper edge of the bar 10 while firmly supported by portion 20b engages and displaces the projecting ends of the latch members 37. See chain line position of packing arm and bar 10 in Figure 3. When the bar 10 has passed beyond the ends of the latch members, the latter fall back to their initial position determined by the pins 38. On lowering of the packing arms, therefore, the bar 10, delivered to position shown in full lines in Figure 3, is engaged at its upper edge by the ends of the latch members 37 and is thereby supported in stable equilibrium. When the next bar 10 is similarly delivered, the initial bar 10 is moved forward thereby and both bars are then supported by the latch members 37. Upon further delivery of bars 10 to form a pack, they will be held together by friction between the individual bars, except for the bar last delivered which will separate from the pack to be supported by latch members 37, as indicated in Figure 4. In this manner a complete pack is progressively built up, successive bars 10 first displacing the latch members and then engaging the ends thereof as the packing arms return after delivering the bars.

When the pack has been fully built up, the leading bar comes to the end of the pack an-

nealing section 16 and immediately falls downwardly over the sloping skid portion 17 with a clean separation from the remaining bars of the pack.

When it is desired to pack-anneal bars of the maximum width, e. g., 8", the shaft 29 is rotated so as to shift the arms 23 from the solid line position to the chain line position shown in Figure 1. The apparatus is then in a position to handle the widest bars which are delivered to the packing section 16 in the manner already described in handling relatively narrow bars. The wide bars, however, being engaged at a different point along the face 20b of the arms 20, are carried up to a position nearer to the vertical, as shown in Figure 5, than the final position of the narrow bars, as shown in Figure 3. As in the case of the narrow bars, each wide bar delivered by the packing arms displaces the latch members 37, as shown in Figure 5, but, on retraction of the packing arms, comes to rest against the ends thereof. By reason of their greater width, the bars 10' are deposited on the packing section 16 at a lesser angle to the vertical than the bars 10 in order to obtain desired stability of pack and also to reduce to a minimum the lateral pressure against the ends of the latch members 37. The complete pack of wide bars is built up in the manner already explained in handling relatively narrow bars, and as illustrated in Figure 6, and the discharge of the leading bar takes place automatically on completion of the pack, as previously described.

Several of the advantages of my invention have been mentioned above in the course of the detailed description. As already stated, the invention provides an improved cooling bed having simple and relatively inexpensive provisions for the pack annealing of bars of various widths up to a maximum of approximately 8" or the maximum the cooling bed as a whole is suited to handle. In this respect, the invention is a marked improvement over prior pack annealing cooling beds since the pack supporting members of the latter would have to be made large and cumbersome to accommodate bars of a width as great as 8" and would unduly increase the width and the cost of the cooling bed as a whole. In addition, the leading bar of the pack separates itself quickly and cleanly from the remainder of the pack as a succeeding bar is delivered to the entry side thereof.

The width of the pack annealing section of the bed may be chosen as the theoretical minimum required in view of the maximum width of the bars to be annealed, the length of the cooling bed and the rolling speed of the mill delivering bars to the bed. This is not the case with existing beds above referred to which are partially ineffective due to "shingling" on the pack annealing section. Regardless of the width of the pack annealing section, the invention provides means for laterally supporting rolled bars of various widths on edge as they progress through the packs from the entering side to the discharge side thereof.

As shown in Figure 5, the travel of the upper edges of the bars subject to annealing beyond the ends of the pack supporting latch members 37 is greater in the case of wide bars than in the case of the narrow bars. Nevertheless, since the outer extremities of the packing arms 20 have a greater linear velocity than the inner portions, the time allowed for the members 37 to drop after displacement is practically the same regardless of the width of the bars being annealed. The latch

members are relatively thin, as shown in Figure 2, to reduce their weight and the friction exerted thereby on the upper edges of the bars as the latter are delivered progressively by the packing arms. Furthermore, due to the shape of portions 20a and 20b, the bars in transit to the packing section 16 are firmly supported at their upper edges while these edges force the displacement of the latch members 37. Obviously, the friction between the upper edges of the bars and the latch members 37 is much less than that between the lower edges of the bars and the surfaces defining the arcuate skid section 15. This assures that the bar being delivered is maintained in stable equilibrium until finally deposited on the pack annealing section and resting against the latch members.

The travel of the upper edges of the bars subject to annealing beyond the ends of the pack supporting latch members 37 causes the last bar delivered to the packing section 16 to lean against the ends of the latch members 37 at a greater angle to the vertical than that of the position to which the bar was delivered by the packing arms 20. See Figures 4 and 6. This is of advantage in that each succeeding bar upon delivery to the packing section 16 first engages the previous bar at its upper edge to set it in motion before the lower edge is displaced. This mode of operation increases the stability of the pack during the critical early stage of its formation.

The construction of the links 31 is such as to permit individual adjustment of the arms 23, by turning nuts 35, to align all the pack engaging latch members 37 throughout the length of the bed to insure simultaneous engagement thereof by the bars delivered to the pack annealing section.

Although I have illustrated and described but a preferred embodiment of the invention, it will be recognized that changes in the construction and arrangement may be made without departing from the spirit of the invention or the scope of the appended claims.

I claim:

1. In a cooling bed, a run-in conveyor, a bed section beside the conveyor for the pack annealing of thin flat bars which do not stand on edge without lateral support, means for providing lateral support for a pack on said section comprising arms pivotally mounted back of the conveyor and overhanging the bed, means for swinging said arms to accommodate bars of various widths, and a latch member pivoted to the free end of each arm adapted to be displaced by a bar being delivered on edge to said section and adapted thereafter to return to its original position in which it is engaged by the upper edge of said bar after delivery thereof.

2. In a cooling bed, a run-in conveyor, a bed section beside the conveyor for the pack annealing of thin flat bars which do not stand on edge without lateral support, means for providing lateral support for a pack on said section comprising arms pivotally mounted back of the conveyor and overhanging the bed and a latch member pivoted to the free end of each arm adapted to be displaced by a bar being delivered on edge to said section and adapted thereafter to return to its original position in which it is engaged by the upper edge of said bar after delivery thereof, means for successively delivering bars to said section on edge and in a position permitting such return of the latch member, and means for simultaneously adjusting all said arms toward or from said section to adjust said latch member to different levels for supporting packs of bars of various widths.

20 3. The apparatus defined by claim 1 characterized by said latch members being operative to restore themselves to bar-holding position within substantially the same time interval for all adjusted positions of said arms.

25 4. In a cooling bed, a run-in conveyor, a bed section beside the conveyor for the pack annealing of thin flat bars which do not stand on edge without lateral support, means for providing lateral support for a pack on said section comprising arms overhanging the bed, a latch member pivoted to the free end of each arm adapted to be displaced by a bar being delivered on edge to said section and adapted thereafter to return to its original position in which it is engaged by the upper edge of said bar after delivery thereof, and means back of said conveyor supporting said arms for movement in a vertical plane to adjust the level of said latch members.

30 5. In a cooling bed, a run-in conveyor, a pack-annealing section beside the conveyor, and means to support a pack of bars on said section, said means including arms overhanging the bed, a latch member pivoted to the free end of each arm and adapted to be displaced by a bar being delivered on edge to said section said member being overbalanced in such direction as to return by gravity to its original position in which it is engaged by the upper edge of the delivered bar, a downwardly inclined skid section adjoining said pack-annealing section, and means for delivering bars successively to said pack-annealing section in rearwardly leaning position relative to the direction of travel of the bars thereacross whereby the leading bar of the pack is left free to slide down the inclined section when it reaches the discharge side of the pack-annealing section.

GUSTAF L. FISK.
